COMBINED FLOOR WASHER, WAXER, AND DUSTER

Carolyn Gail Wien, 42—42 Colden St., Flushing, N.Y.

Filed July 23, 1962, Ser. No. 71,019

Term of patent 14 years

(Cl. D9—2)

FIG. 1 is a front perspective view of a combined floor washer, waxer, and duster, showing my new design.

FIG. 2 is a side elevational view thereof.

FIG. 3 is a rear elevational view thereof.

I claim:

The ornamental design for a combined floor washer, waxer, and duster, substantially as shown.
